CLAIM

The ornamental design for a pillar having a rotating spherical pivot, as shown and described.

DESCRIPTION

FIG. 1 is a perspective view of the pillar having a rotating spherical pivot showing my new design.

FIG. 2 is an another perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

The broken lines are included for the purpose of illustrating portions of the pillar having a rotating spherical pivot and form no part of the claimed design.

1 Claim, 8 Drawing Sheets
